UNITED STATES PATENT OFFICE.

GUSTAVE O. CARLSON, OF WETHERSFIELD, CONNECTICUT, ASSIGNOR TO MAYHEW
STEEL PRODUCTS, INC., OF NEW YORK, N. Y., A CORPORATION OF DELAWARE.

HAND TOOL.

Application filed January 14, 1921. Serial No. 437,217.

To all whom it may concern:

Be it known that I, GUSTAVE O. CARLSON, a citizen of the United States, and a resident of Wethersfield, in the county of Hartford, State of Connecticut, have invented certain new and useful Improvements in a Hand Tool, of which the following is a specification.

This invention relates particularly to 10 hand-tools of the type comprising a pair of pivotally connected members each with a handle at one end and an active or fabricating portion at the other end. The invention is here illustrated as embodied in pliers, but 15 it is to be understood that the present disclosure is illustrative only and is not to be taken as restrictive of my invention.

The object of the present invention is to provide a hand-tool of this sort having features of novelty and advantage and which is characterized particularly by its simplicity of construction, economy in manufacture, and its great strength and durability.

In the accompanying drawing:—

25 Fig. 1 is an elevational view of my improved pliers.

Fig. 2 is an edge view, with a portion broken away, of that member having the integral pivot stud, and

30 Fig. 3 is a sectional view taken on line 3—3 of Fig. 1.

A pair of pliers constructed in accordance with the present invention consists of two members A, B, each preferably formed in 35 one piece by forging. Each part has a handle portion 10 and an active or jaw portion 11 at its opposite ends. One of the members, in the present instance part A, has between its jaw and handle portions an integral stud 13 which is received by a similarly positioned bearing in the other member B, this bearing in the present instance being in the form of an aperture 14. This 40 aperture 14 is preferably countersunk as at

15 and the outer end of the stud 13 is bent 45 or headed over into the countersink.

Preferably the stud 13 is recessed at its end so that during the heading or riveting operating expansion of the body portion of the stud into binding engagement with the 50 wall of the aperture 14 is eliminated. The annular lip 16, provided by recessing the stud, is of some thickness, as shown in Fig. 3, so that after this lip is headed over, it is 55 of sufficient strength to securely hold the parts together against the relatively great strains to which tools of this sort are subjected.

It will be seen that a tool constructed in accordance with the present invention consists of two parts each of which is of very simple construction. This makes it possible to forge each of these parts and connect them together without resorting to machining operations which materially increase 60 the cost of tools of this sort. Thus is provided a tool which is very strong, durable and of pleasing appearance and which may be manufactured and placed on the market at a very reasonable price. 70

I claim as my invention:—

A pair of pliers comprising two forged members each having a handle portion and a jaw portion, one of said members having a cylindrical aperture between its handle 75 and jaw portions, said aperture being bevelled or counterbored at one end to provide a recess of substantial area and the other of said members having between its handle and jaw portions an integral stud of greater 80 height than the length of the aperture in said other member, said stud having a recess in its outer end to provide an annular lip, said lip being bent over into the countersink of said aperture and being of substantial 85 thickness, whereby it has sufficient strength to withstand strains.

GUSTAVE O. CARLSON.
